Primary Examiner — Darcey E Gottschalk(57) **CLAIM**

The ornamental design for a medical testing processing device, as shown and described.

DESCRIPTION

1. Medical testing processing device

1.1 : Top perspective view

1.2 : Top

1.3 : left side view

1.4 : Front

1.5 : right side view

1.6 : Bottom perspective view

1.7 : Bottom

1 Claim, 7 Drawing Sheets(56)
